(57) **CLAIM**

The ornamental design for a rotating wrist support, as shown and described.

DESCRIPTION

FIG. 1 is a perspective view of the rotating wrist support embodying the design of the present invention;

FIG. 2 is a front elevational view thereof;

FIG. 3 is an end elevational view thereof;

FIG. 4 is a top plan view thereof; and,

FIG. 5 is a bottom plan view thereof.

The broken line showing of environment is for illustrative purposes only and forms no part of the claimed design.

1 Claim, 3 Drawing Sheets

FIG. 4.

FIG. 2.

FIG. 3.

FIG. 5.
